UNITED STATES PATENT OFFICE.

ROBERT M. SWINDLER, OF OTTAWA, AND GEORGE L. BRADSHAW, OF TOPEKA, KANSAS.

HORSE COLLAR.

Application filed December 29, 1923. Serial No. 683,394.

To all whom it may concern:

Be it known that we, ROBERT M. SWINDLER and GEORGE L. BRADSHAW, citizens of the United States, residing, respectively, at 5 Ottawa and Topeka, in the counties of Franklin and Shawnee and State of Kansas, have invented a new and useful Horse Collar, of which the following is a specification.

10 This invention relates to horse collars, and one of its objects is to provide a collar with a top pad designed to protect the collar from wear by hames and also designed to prevent the hames from slipping forwardly 15 when in position on the collar.

A further object is to provide a protecting pad which will afford full protection even when the collar is lengthened, said pad serving to hold the ends of the collar at all 20 times properly positioned relative to each other.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 25 30 within the scope of what is claimed without departing from the spirit of the invention.

In the accompanying drawings the preferred forms of the invention have been shown.

35 In said drawings—

Figure 1 is a front elevation showing one form of pad detachably mounted on a horse collar, a portion of the collar being shown by broken lines.

40 Fig. 2 is a plan view of the structure shown in Fig. 1.

Fig. 3 is a section on line 3—3, Fig. 2.

Fig. 4 is a front elevation showing another form of pad applied to a portion of 45 a collar shown by broken lines.

Fig. 5 is an enlarged section on line 5—5, Fig. 4.

Referring to the figures by characters of reference A designates the side portions of 50 a collar of the usual construction and in the present instance there is provided an attachment comprising a lower pad 1 and an upper pad 2. The lower pad is formed of heavy leather so shaped as to fit snugly within 55 the top portion of the collar and has straps 3 riveted or otherwise fastened to the front

and back edges thereof preferably adjacent the ends and middle portions. These straps are extended into and suitably fastened to the front and rear edges of the top pad 2 as 60 clearly illustrated in Fig. 3, it being seen that the top pad is composed of two thicknesses of leather indicated at 4 and 5. A filling strip 6 is interposed between the two thicknesses 4 and 5 along the front edge 65 portions thereof so as to offset the upper thickness or layer 5 and thus produce a longitudinal outstanding rib. The layers of the top pad are fastened together longitudinally close to and back of the rib and 70 also at their ends. The space between the rear edge of the pad 2 and the intermediate point of attachment, 7, between the layers of the pad forms a longitudinal casing 8, there being slots 9 in the top layer 5 close 75 to the ends of the casing. These slots are adapted to receive a strap 10 one end of which is riveted or otherwise fastened to one side of the collar while the other end is 80 adapted to be engaged by a buckle 11 attached to the other side of the collar. Consequently when the top portion of the collar is placed between the upper and lower pads it can be properly held assembled therewith by means of the strap 10 and the buckle 11, 85 it being obvious that by loosening the strap the upper end of the collar can be opened out and the pad, by reason of its flexible nature, will adjust itself to the shape of the collar when thus enlarged. 90

Instead of connecting the front and back edges of the lower and upper pads by means of straps that are not detachable from the pads, as shown in Figs. 1, 2 and 3, the lower pad 12 and the upper pad 13 can be made 95 separate as illustrated in Figs. 4 and 5. In this form of device, the lower pad 12 has straps 14 riveted or otherwise fastened to one edge portion thereof and provided with buckles 15 adapted to be adjustably engaged 100 by straps 16 riveted or otherwise fastened to the opposite edge portions of the pad. These straps are adapted to be extended around the adjacent portions of the collar A for the purpose of fastening the lower 105 pad in position. The upper pad 17 is separate from the lower pad but is of practically the same construction as the pad illustrated in Figs. 1, 2 and 3.

This pad 17 consists of lower and upper 110 layers 18 and 19 of leather fastened together at their edges and at intermediate points,

there being a filling strip 20 between the layers near the front edge to provide a longitudinal rib and there being a casing 21 back of the rib for the reception of the strip 5 22 used for connecting the upper ends of the collar.

In both structures a rib is provided for the purpose of preventing the hames from slipping forward and in both instances the 10 pads constitute means for protecting the collar from wear by the hames. The pads protect the collar when adjusted to different widths at the top and the pads are also so mounted as to be properly retained at all 15 times while in use.

What is claimed is:—

1. An attachment for horse collars comprising lower and upper pads for receiving a portion of a collar therebetween, a strap 20 receiving casing extending longitudinally of the upper pad, and a retaining rib extending longitudinally of said upper pad and outstanding therefrom.
2. An attachment for horse collars including upper and lower pads for the reception 25

of a portion of a collar therebetween, connections between the front and back of the pads, said upper pad including superposed layers of material fastened together at their edges and longitudinally at an intermediate 30 point, a filling strip interposed between the layers to provide an outstanding retaining rib, and the portion of the pad back of the retaining rib constituting a strap receiving casing open at its ends.

3. A top pad for horse collars comprising superposed layers of material fastened together at their edges and longitudinally between their edges, a filler interposed between said layers adjacent the front edges to provide an outstanding retaining rib, and the upper layer having transverse slots adjacent the ends of the pad and opening into the space between the rear portions of the layers, thereby to provide a strap receiving casing. 40

In testimony that we claim the foregoing as our own, we have hereto affixed our signatures.

ROBERT M. SWINDLER.
GEORGE L. BRADSHAW.
